BASEBALL PADDLE GAME BOARD OR SIMILAR ARTICLE

Lawrence B. Wittmann, Sr., 82 N. Munn Ave.,
Newark, N.J.

Filed Feb. 25, 1960, Ser. No. 59,525

Term of patent 7 years

(Cl. D34—15)

The dominant features of my design reside in those portions of the drawing shown in full lines.

This application is a continuation in part of co-pending application, Serial No. D. 55,777, filed May 5, 1959, now abandoned.

I claim:

The ornamental design for a baseball paddle game board or similar article, as shown and described.
